STRAIGHTEDGE

Harry H. Warner and Thomas Keller, Minneapolis, Minn., assignors to Warner Manufacturing Company, Minneapolis, Minn., a corporation of Minnesota

Application September 24, 1931
Serial No. 564,762

3 Claims. (Cl. 167—73)

Our present invention relates to straightedges and more particularly to metallic straightedges intended for general use but especially well adapted for paperhangers for use in guiding a knife or trimmer when cutting or trimming a roll of wall paper or similar wall covering before applying the same to a wall.

Straightedges now commonly used by paperhangers are either made entirely of wood or of wood that is metal reinforced or metal bound, or both, and are objectionable for the reason that they soon get out of true due to their moisture contents and climatic changes.

The object of this invention is to provide a hollow metal straightedge that is of light-weight and that will not bend, twist, contract or expand, and hence, will always guide a knife or trimmer in a true straight line.

To the above end, generally stated, the invention consists of the novel construction and arrangement of parts hereinafter described and defined in the claims.

In the accompanying drawing, which illustrates the invention, like characters indicate like parts throughout the several views.

Referring to the drawing:

Fig. 1 is a fragmentary perspective view of the improved straightedge;

Fig. 2 is a bottom plan view of one of the end portions of the straightedge;

Fig. 3 is a view in transverse section taken on the line 3—3 of Fig. 1; and

Fig. 4 is a fragmentary detail view in longitudinal section taken on the line 4—4 of Fig. 1.

The body 5 of the straightedge is hollow, rectangular in cross-section and, as shown, is formed from a single sheet of metal 6 that was primarily flat. The longitudinal edge portions of the sheet 6 form the top member of the body 5 and are spaced to form a groove or way 7 that extends the full length of the straightedge. This way 7 is relatively close to the trimming edge 8 of the straightedge and with which it cooperates for guiding a paper or other trimmer, not shown. Either edge of the straightedge may be used for guiding a knife held in the hand of the operator and having either a straight blade or a cutting wheel.

A reinforcing rib 9, which extends the full length of the straight edge, is pressed from the bottom member of the straightedge. This reinforcing rib 9 extends into the hollow body 5, is in the form of an inverted U and the top member 55 of said body, at the inner edge of the way 7, rests

on the crown of said rib and is rigidly secured thereto by rivets 10.

The ends of the body 5 are closed by filler blocks 11 that are rigidly secured thereto by rivets 12. The outer faces of the filler blocks 11 are flush 60 with the ends of the body 5 and have in their tops notch-like passageways 13 arranged to permit a trimmer for paperhangers and of any well known make to enter the way 7 from either end of the straightedge and move the full length of said 65 straightedge during trimming action.

The drawing illustrates a commercial form of the invention, but it will be understood that the same is capable of certain modifications as to details of construction, arrangement and combination of parts within the scope of the invention herein disclosed.

What we claim is:

1. A hollow straightedge formed from a primarily flat single sheet of metal, the exterior of 75 the straightedge, in cross-section, being a rectilinear parallelogram, the distance between the parallel upper and lower members of the straightedge being materially less than the distance between the parallel edge members thereof, the bottom member of the straightedge being pressed inwardly to form an inverted U-shaped bead the crown of which affords a support for the top member of the straightedge, the width of the bead being relatively narrow with respect to the width 85 of the straightedge, the edges of the sheet being at the top of the straightedge and between one of its edge members and the bead and spaced to leave a way therebetween.

2. The structure defined in claim 1 which further includes filler blocks closing the open ends of the straightedge, the top member of the straightedge being rigidly secured to the filler blocks on each side of the way.

3. A hollow straightedge formed from a primarily flat single sheet of metal, the exterior of the straightedge, in cross-section, being a rectilinear parallelogram, the distance between the parallel upper and lower members of the straightedge being materially less than the distance between the parallel edge members thereof, the edges of the sheet being at the top of the straightedge and spaced to leave a way therebetween, and filler blocks closing the open ends of the straightedge, the top member of the straightedge being 105 rigidly secured to the filler blocks on each side of its way.

HARRY H. WARNER.
THOMAS KELLER.
